FIG. 1.

FIG. 2.

Inventor
Thomas O'Donnell,

Say *C. L. Parker* *Attorney*

UNITED STATES PATENT OFFICE.

THOMAS O'DONNELL, OF IRONWOOD, MICHIGAN.

DESIGN FOR AN ELECTRIC-LIGHT RECEPTACLE.

53,375.

Specification for Design.

Patented May 27, 1919.

Application filed January 18, 1917. Serial No. 143,182. Term of patent 14 years.

To all whom it may concern:

Be it known that I, THOMAS O'DONNELL, a citizen of the United States, residing at Ironwood, county of Gogebic, and State of Michigan, have invented a new, original, and ornamental Design for an Electric-Light Receptacle, of which the following is a specification, reference being had to the drawing, forming a part thereof.

Figure 1 is a plan view of a receptacle embodying the invention, and,

Copies of this patent may be obtained for five cents each, by addressing the "Commissioner of Patents, Washington, D. C."

Fig. 2 is a side elevation of the same.

I claim:

The ornamental design for an electric light receptacle, as shown.

THOMAS O'DONNELL.
